UNITED STATES PATENT OFFICE.

WILLIAM M. WHITE, OF MILWAUKEE, WISCONSIN.

HYDRAULIC TURBINE.

Application filed July 18, 1921. Serial No. 485,522.

To all whom it may concern:

Be it known that WILLIAM M. WHITE, a citizen of the United States, residing at Milwaukee, in the county of Milwaukee and 5 State of Wisconsin, has invented a certain new and useful Improvement in Hydraulic Turbines, of which the following is a specification.

This invention relates in general to improvements in the art of constructing hydraulic machinery, and relates more specifically to an improved hydraulic machine structure and to an improved method of manufacturing hydraulic impellers.

10 An object of the invention is to provide a hydraulic machine which is simple in construction and efficient in operation. Another object of the invention is to provide an improved method of manufacturing impellers for hydraulic machines. A further object of the invention is to provide simple and efficient means for preventing destruction of hydraulic impellers by pitting or wear, and for effecting repair of pitted or 20 worn impellers. These and other objects and advantages of the present invention will be apparent from the following description.

It has been found desirable in the art of converting hydraulic energy into useful 30 work, to operate the rotors or impellers at relatively high speed. In order to insure sufficient strength in impellers of hydraulic machines operable at high speed, it is desirable to construct the impeller of one piece, 35 that is, with the hub, vanes and rim formed integral. The efficient operation of hydraulic machines at high speed also necessitates formation of the hydraulic passages between impeller vanes, of such shape that 40 pitting or wear occurs at local spots on the leading vane faces near the discharge end of the impeller, and is likely to occur at places where eddies may form. The pitting is sometimes augmented by the presence of 45 sand and gravel in the water and generally occurs at substantially the same place on each of the successive impeller vanes.

In order to avoid necessity of replacing an entire impeller or the vanes thereof, due 50 to pitting or wear, the present invention contemplates the provision of simple and efficient means for appreciably eliminating pitting of the turbine vanes and for permitting rapid repair of pitted impellers in cases 55 where pitting cannot be entirely eliminated. With the present invention the impeller is

constructed with recesses at the places on the vanes where pitting would naturally occur, and is provided with readily renewable wear plates embedded within the vane 60 recesses. When pitting or wear occurs in an impeller so constructed, the impeller may be quickly and conveniently repaired at minimum cost, and with minimum loss of operating time.

A clear conception of an embodiment of the invention and of the improved method of manufacturing impellers, may be had by referring to the drawing accompanying and forming a part of this specification in which like reference characters designate the same or similar parts in the several views;

Fig. 1 is a central vertical section through a hydraulic turbine impeller of the Francis type, showing local wear plates applied to 75 the vanes.

Fig. 2 is a fragmentary bottom view of the hydraulic impeller provided with local wear plates, looking at the delivery end of 80 the impeller.

Fig. 3 is a developed vertical section through the impeller vanes and the wear plates, the section being taken along the line III—III of Fig. 1 looking in the direction of the arrows.

While the invention is illustrated herein as specifically applied to a "Francis" type of impeller it will be obvious that the principles are more generally applicable to other types of hydraulic impellers. The Francis impeller comprises in general a central hub 2, an annular series of vanes 3 formed integral with the hub 2, and an outer rim 4 secured to the outer extremities of the vanes 3. The one-piece impeller is preferably 90 formed by casting and the hub 2 is bored for attachment to a main shaft 5. The hub 2 has a generally conical contour whereby the water is properly guided through the impeller, and the end of the hub 2 adjacent to the impeller discharge may be provided 95 with a removable cap 6 as shown.

Each of the impeller vanes 3 is curved and is provided with a local recess having 105 tapered side walls 8, the recess being located near the discharge end 10 of the impeller. Located within each of the recesses of the impeller vanes 3, is a wearing plate 7 the outer surface of which is flush with the adjacent surface of the vane 3 thus forming 110 a smooth surface for guiding the water. The wear plates 7 may be attached to the

vanes 3 either with the aid of cap screws 9 as shown, or by riveting, or by spot welding, or by caulking, or by casting the metal directly into the vane recesses. The wear 5 plates 7 may also be formed either of the same or of different material than that of the impeller vanes. It may in some cases be desirable to form the impeller vanes of cast iron and to employ steel or bronze wear 10 plates. The recesses in the vanes 3, may also be located at various places and each vane may if desired be provided with more than one recess and wear plate 3 therein depending upon the impeller design. 15 The impeller and the recesses in the vanes 3 thereof, are preferably formed by casting, the wear plates 7 being subsequently applied. The wear plates should, however, be made readily detachable in order to permit 20 rapid and convenient renewal thereof. By thus forming the impeller and the wear plates, the cost of repair of the impeller is reduced to a minimum and minimum loss of operating time of the unit is entailed by 25 such repair. By embedding the wear plates within the impeller vanes, these plates may be effectively secured against displacement by centrifugal force and smooth hydraulic passages may be readily maintained. It 30 will also be obvious that in cases where the tendency of pitting is slight, the wear plates may be permanently secured to the impeller vanes, the plates being formed of material capable of more readily resisting the pitting 35 action.

It should be understood that it is not desired to limit the present invention to the

exact details of the structure and of the method of manufacturing impellers, herein shown and described, for various modifications within the scope of the appended claims may occur to persons skilled in the art. 40

It is claimed and desired to secure by Letters Patent: 45

1. In a hydraulic turbine, an impeller comprising a series of vanes each having a face subjected to liquid pressure and having an opposite face subjected to suction during normal operation of the turbine, each of said vanes being initially formed with a local recess in its suction face at the discharge end of the pressure face of an adjacent vane, and a renewable wear plate secured to each of said vanes within said recess. 50

2. In a hydraulic turbine, an impeller having a hub and a series of vanes formed integral with said hub, each of said vanes having a face subjected to liquid pressure and having an opposite face subjected to suction during normal operation of the turbine and each of said vanes being initially formed with a local recess in its suction face at the discharge end of the pressure face of an adjacent vane, and a renewable wear plate secured to each of said vanes within said recess and having a wearing surface substantially flush with the adjacent suction face of the vane. 60

In testimony whereof, the signature of the inventor is affixed hereto. 65
